UNITED STATES PATENT OFFICE.

OTTO W. HELBIG, OF CHICAGO, ILLINOIS, ASSIGNOR TO OTTO W. HELBIG COMPANY, OF CHICAGO, ILLINOIS, A CORPORATION OF ILLINOIS.

CARD-INDEX FILE.

No. 902,541.

Specification of Letters Patent.

Patented Oct. 27, 1908.

Application filed August 21, 1905. Serial No. 275,080.

To all whom it may concern:

Be it known that I, OTTO W. HELBIG, a citizen of the United States, residing at Chicago, in the county of Cook and State of Illinois, have invented a certain new and useful Improvement in Card-Index Files, of which the following is a specification.

My invention relates to mechanism for accurately accounting for large quantities of goods which will be referred to under the term of "packages," which are sent out by a dealer, and are to be returned when the contents are removed. Under this class may be mentioned freight cars of a railroad, and the casks and cases of bottles used in breweries, though I do not limit myself to the use of the device with any particular sort of packages.

The importance of the device will be understood when it is stated that in some large institutions there are many thousands of returnable packages sent out every month, and if they are not accurately accounted for, heavy financial loss must result.

The object of my invention is to provide a device for this purpose by means of which the attention of the accountant having charge of the accounts relating to the packages is automatically called to, any packages which have been out an undue length of time, so that he will, if he lives up to his duty, immediately institute an investigation as to why these packages have not been returned, and which will, at the same time, enable a shipping clerk who receives a package back with only a number upon it, to readily determine to whom it is to be credited.

My invention consists in a neat and convenient form of mechanism capable of accomplishing the above objects, which can be easily and cheaply made and installed, which can be easily operated, and is not readily liable to get out of order.

It further consists in details of construction which will be hereafter more fully described and claimed as the specification proceeds.

Referring to the drawings, Figure 1 is an isometric perspective view of one drawer of the filing cabinet having a portion of the mechanism of my invention applied thereto; Fig. 2 is a similar view of another drawer having the remainder of the mechanism of my invention applied thereto.

When the device is used by a small concern, the mechanism contained in these two

figures may be mounted in one long drawer of a cabinet, and when the device is used by a large concern having many thousands or hundreds of thousands of packages to be accounted for, the parts of the device may be enclosed in many drawers of a cabinet, or in the drawers of several cabinets, or any other suitable receptacle.

The returnable packages to be accounted for, whether freight cars or liquor cases, or other objects, owned by the business house which is to use the device, should be consecutively numbered from one, or any desired specified number, upward, and the number should be firmly and plainly affixed to each package. Having the returnable packages which are to be accounted for thus numbered, I divide the year into a number of convenient intervals of time suitable for accounting purposes, usually one month. Assuming that this division is made, I provide twelve sets of tabbed record cards *k*, such as are shown in Fig. 1, which are numbered consecutively from the lowest to the highest numbers of the returnable packages which are to be accounted for.

In the drawings, I have shown the cards for fifty packages, and in Fig. 1, these are seen duplicated five times; those in section A being numbered from 1 to 50, and those in section B from 1 to 50, and those in section C from 1 to 50, and so on. Were there 100,000 packages to be accounted for, there would be 100,000 cards consecutively numbered in section A, and the same number in each of the other sections B, C, D, E, and so on, throughout the sections representing the twelve months of the year. If the accountant having charge of the work should determine that periods of two months were sufficient for accounting purposes, there would only be six sections of duplicated sets of cards, while if the accountant should determine upon weekly accounting periods, there would be fifty-two sets of duplicated sections of consecutively numbered cards. The cards, or at least the visible portions of them, of each section representing the selected accounting period, whether it be a week, a month, or two months, are of one color, and the cards for each accounting period are of a color distinctly different from the colors of all of the cards representing the other accounting periods of the year. For convenience, I arrange the tabs upon con-

secutive cards in such a way that, as shown in the forepart of Fig. 1, the tabs run step by step across the cabinet from 1 to 10, and I always have the numeral 1 at the left-hand edge, so that 1, 11, 21, 31, 41, etc., are always in one column lengthwise of the drawer of the cabinet, while 5, 15, 25, 35, 45, etc., are always in one other column running lengthwise of the cabinet, as shown in Fig. 1.

10 If the accountant for some reason should desire to use only even numbers, as 2, 4, 6, 8, 10, 12, and so on, the cabinet could be made with only five tabs running across the drawer, instead of ten, without departing from my invention. In this case the numeral 2 would be at the left-hand column. I also provide in connection with the mechanism heretofore described, a series of places, spaces, or receptacles, to each one of which the name of a 15 customer or other person receiving the package may be applied, and in which cards taken from the device shown in Fig. 1 may be placed in such a position that the numbered tabs upon the cards may be readily examined.

In the particular mechanism illustrated in Fig. 2, I do this by providing a plurality of tabbed cards *m*, *n*, *o*, *p*, and *q*, made movable backward and forward in the box or drawer, 20 but these may be made in rigid position with spaces between them; in either construction it being possible to insert tabbed cards *k* between these name-cards, as shown. The accountant having the business in charge, 25 places the name of one customer on each of the name-tab cards *m*, *n*, *o*, *p*, etc., as shown. For purposes of illustration, the name H. George is applied to the card *m*, E. Brown to the card *n*, S. Black to the card *o*, F. Haines 30 to the card *p*, and Charles Knox to the card *q*. Assuming now that the device has been in use for three months, and we are at present doing business in the month in which the cards bearing the color of section C are 35 used. When, now, during this month, indicated by color C cards, a package which is to be accounted for is sent out, to a customer, as, for instance, a package bearing the number 17, on the sale being reported the accountant takes a card bearing number 17 40 from color C section, and places it in the receptacle shown in Fig. 2, bearing the name of the customer to whom this package No. 17 has been delivered. In Fig. 2, Mr. S. Black 45 has, during the month indicated by color C, purchased two packages of goods, one number 17 and one number 44, and these packages have been charged to him by placing the cards bearing these respective numbers and 50 the color C indicating the month in which the delivery was made, in the receptacle or space bearing the name of Mr. Black. This description shows the principle. On this principle, referring to Fig. 2, it will be understood 55 that Mr. H. George has purchased, 60

during the month indicated by the color A, a numbered package bearing the number 15, and that four months later, in the month indicated by the color E, he purchased a package No. 48; the card 48 E in the space bearing his name in Fig. 2, indicating this.

The advantages of the device will be readily understood by the following example. Suppose, first, that we are doing business in the month indicated by the color D. The accountant having charge of the work, running over the drawer or drawers, or other devices containing the receptacles bearing the customers' names, on going to the drawer shown in Fig. 2, notices a card 15 of the color indicated by the letter A in the receptacle bearing the name of H. George. He at once knows that Mr. George has had a package 15 belonging to the main house for over four months, and that it is probably empty and should be returned. He thereupon institutes an inquiry as to why this package has not been returned, with the result that it probably is returned in a short time. If only one set of cards having one color were 90 used for the entire set of numbered packages put out by the original house, he would have to look down at notations upon the tab-cards to see when the package of that number was delivered and as such notations 95 would be normally covered by the card in front he would have nothing to call his attention to the fact that package had been out an undue time, whereas, with this system the minute he sees a card bearing the 100 color which he knows is in a delinquent month or other period of time, his attention is at once called to it, to institute the search just described. The other use of the device is this: In large houses having a large number 105 of numbered packages to be accounted for, a customer frequently returns a numbered package and forgets to send in a memorandum that it is from him. Suppose, now, the shipping clerk receives a package 110 numbered 13, and that there are 100,000 returnable packages belonging to the house; how is he to ascertain to whom this package should be credited? In the use of this device, the matter is referred to the accountant 115 who takes the portion of the mechanism illustrated in drawer 1, and simply looks down column 3 from the left at the cards of each color until he finds a card 13 missing, and as only one card can be missing of this 120 number, it must have a specified color, which, on examining the device in Fig. 1, we find is a card indicated by color B. He now refers to the portion of the device indicated in Fig. 2 and runs down the third column, without 125 paying special attention to the figures, for cards bearing color B; and, if he finds more than one, continues the search until he finds card 13 of color B, which he finds in the account of Mr. E. Brown. He immediately 130

gives Mr. Brown credit on account of package 13, removes card 13 color B from the portion of the device shown in Fig. 2, and places it in its proper place in the drawer in the device of Fig. 1, when the card is ready to be used when, next year, the period of time indicated by color B comes around.

It will readily be seen by the foregoing description that an accountant who has charge of the drawers containing the portion of the device shown in Fig. 2 constantly has his attention called to any returnable packages which are out and which have not been returned as promptly as they should be, and that when a numbered package is returned without any other description than the number, it is very easy to locate it without reading a great quantity of numbers and without examining the matter on the cards below the tabs, to, determine to whom this package is to be credited.

As every card k appearing in Fig. 2 is seen to be missing from the portion of the device in Fig. 1 it is manifest that the accountant, when operating in current month D has his attention called to delinquent unreturned packages sent out in month A by simply examining the cards of month A and that he can locate to whom the packages represented by the missing cards have been sent by the method described in the last paragraph.

The ruled spaces on the bodies of the tab-cards k , in Fig. 1, may be used to make any desirable notes about the numbered package represented by the card. They do not, however, form a part of this invention.

Having thus described my invention, what I claim as new and desire to secure by Letters Patent is

1. A device for use by a dealer in accounting for numerous consecutively numbered returnable packages comprising a set of record cards for each of several specified periods of time; the cards for each set being the same color and of a different color from the cards of all the other sets and having exposed tabs

numbered consecutively to correspond with the successive numbers of the packages to be accounted for; and a plurality of places, spaces or receptacles convenient to the main groups of cards to each of which a customer's name may be applied and in which one of said numbered cards corresponding with the number of the package delivered to said customer taken from the set of cards of the color indicating the period of time in which delivery of said package is made to said customer may be placed.

2. A device for use by a dealer in accounting for numerous consecutively numbered returnable packages comprising: a set of record cards for each of several specified periods of time; the cards in each set being the same color and of a different color from the cards of all the other sets and having exposed tabs numbered consecutively to correspond with the successive numbers of the packages to be accounted for, the tabs on each ten or less successive cards being arranged step by step across the width of the cards with the lowest unit of the consecutive numbers of the tabs at the left and the same unit always in the same position on all the cards bearing that unit as described; and a plurality of places, spaces or receptacles convenient to the main groups of cards, to each of which a customer's name may be applied and in which one of said numbered cards corresponding with the number of the package delivered to said customer taken from the set of cards of the color indicating the period of time in which delivery of said package is made to said customer, may be placed in such a position that the numbered tabs on the cards of successive customers are exposed to view.

In witness whereof, I have hereunto subscribed my name in the presence of two witnesses.

OTTO W. HELBIG.
